UNITED STATES PATENT OFFICE.

MILLARD F. CHANDLER, OF CHANDLER SPRINGS, ALABAMA.

CHURN-LID CLAMP.

1,279,513.

Specification of Letters Patent. Patented Sept. 24, 1918.

Application filed February 9, 1918. Serial No. 216,418.

To all whom it may concern:

Be it known that I, MILLARD F. CHANDLER, a citizen of the United States, residing at Chandler Springs, in the county of Talladega and State of Alabama, have invented 5 certain new and useful Improvements in Churn-Lid Clamps, of which the following is a specification.

This invention has relation to churning and 10 has for an object to provide a clamp for securing the cover in place.

Another object of the invention is to provide a churn cover clamp constructed entirely of wire, having its parts formed in a 15 manner to permit the rapid and facile engagement of the clamp upon the cover and the securing of the cover in place.

Another object of the invention is to provide a cover clamp designed to extend entirely across the top of the cover with members 20 to be arranged centrally around the plunger rod whereby to reinforce somewhat the cover.

A still further object of the invention is 25 to provide a churn cover clamp of the character above set forth which is extremely simple in construction, and which may be manufactured at a nominal cost.

In addition to the foregoing my invention 30 comprehends improvements in the details of construction and arrangement of the parts to be hereinafter more fully described and particularly set forth in the appended claims.

35 In the accompanying drawings in which similar and corresponding parts are designated by the same characters of reference throughout the several views in which they appear:—

40 Figure 1, is a view in plan of my improved churn cover clamp, illustrating the contour of the cover and the association thereto in dotted lines.

Fig. 2, is a view of the device in side elevation, and

45 Fig. 3, is a section taken on line 3—3 of Fig. 2.

With reference to the drawings, 10—10 indicates a pair of clamping members in the 50 form of strands of wire having their ends bent at right angles to form members 11 to engage the periphery of the cover, and the extremities of the said members 11 bent inward as at 12, the length of the portion 55 11 corresponding to the combined thickness of the cover indicated in dotted lines at 13,

and the flange 14 or other portion of the churn to which the cover is secured. The members 10 are disposed in parallelism and connected by means of connecting members 60 15, a pair of which are provided, the same comprising sections of wire having their terminals bent to form loops 16 through adjacent loops of which the clamping members 10 extend. The extremities of the members 65 15 are then bent downward as at 17 to engage the top surface of the cover. The members 15 are slideable along the members 10 toward or away from the end thereof defining, with the members 10 a rectangular inclosure for 70 75 the plunger rod indicated at 18 in dotted lines.

It will be noted that the members 10 are rotatable relative to each other within the loops of the members 15, and the clamp is 80 applied to the top surface of the cover while the members 11 of the clamping members 10 are pointed in opposite directions, the said members subsequent to the application of the clamps to the cover being brought toward each other so as to depend and be disposed beneath the flange 14 of the churn as in Fig. 2.

To secure the clamping members in adjusted position, I provide braces indicated 85 at 19. A pair are provided, each in the form of a strand of wire having one end bent to form a loop 20 which is engaged around members 11 of one clamp 10 while the opposite ends of said braces are formed 90 with hook-shaped terminals 21 to engage around the members 11 of the other clamp 10 as shown in Fig. 1 of the drawings. Owing to the curvature of the cover and flange 14 the members 11 are tightly 95 engaged against the periphery thereof, while the braces 19 extend beneath the flange 14 thereby preventing removal of the clamp and cover. The parts of the clamp should be so dimensioned as to cause the members 100 thereof to be placed slightly under strain when adjusted in the manner stated and to flex the members 10 somewhat causing the terminals 17 and loops 16 of the bracing members 15 to bear against the cover.

105 From the foregoing it will be apparent that I have provided a clamp which is not only simple in construction in that its parts are of simple configuration, but also in which the parts are largely duplicates. It 110 will be seen that the parts 15, 10, and 19 correspond to one another and hence only three

parts of the same configuration are necessary to form a clamp containing six parts in all.

While I have illustrated and described my invention with some degree of particularity, I realize that in practice various alterations thereover may be made, and I therefore desire to reserve the right and privilege of changing the form of the details of construction, or otherwise altering the arrangement of the correlative parts without departing from the spirit of the invention or the scope of the appended claims.

Having thus described my invention what I claim as new and desire to secure by Letters Patent is:

1. A clamp for churn covers, including parallel members to extend across the cover of a length slightly less than the diameter thereof, depending portions formed on the terminals of said members to engage the periphery of the cover, arms pivotally connected to the depending portions of one member, hook shaped terminals formed upon the other ends of said arms, to releasably engage the depending portions of the other clamping member, and a pair of rods hav-

ing their ends formed with loops to receive the clamping members for spacing said clamping members apart, the terminals of said rods extending beyond the loop and resiliently engaging the cover to secure the same in place.

2. A clamp for churn covers, comprising a pair of substantially parallel rods having their terminals bent to form loops and extensions bent downwardly to resiliently engage the cover, a second pair of substantially parallel rods extending at right angles to the first pair of rods and rotatably and slidably mounted in the loops of said first pair of rods, depending arms formed on the ends of the second pair of rods and having their ends formed into hooks, and means connected to the depending arms of one parallel rod for engaging the depending arms of the other parallel rod.

In testimony whereof I affix my signature in presence of two witnesses.

MILLARD F. CHANDLER.
